[57] CLAIM

The ornamental design for a tent, as shown and described.

DESCRIPTION

FIG. 1 is a perspective view of a tent showing my new design;

FIG. 2 is a side elevational view thereof, the other side being a mirror image;

FIG. 3 is an end elevational view thereof, the other side being a mirror image; and,

FIG. 4 is a top plan view thereof.

The bottom of the design forms no part of the claim.
